UNITED STATES PATENT OFFICE.

CHARLES W. DENNY, OF PHILADELPHIA, PENNSYLVANIA.

HANGER-SOCKET.

1,109,115

Specification of Letters Patent.

Patented Sept. 1, 1914.

Application filed May 21, 1912. Serial No. 765,336.

To all whom it may concern:

Be it known that I, CHARLES W. DENNY, citizen of the United States, and a resident of the city and county of Philadelphia, State of Pennsylvania, have invented an Improvement in Hanger-Sockets, of which the following is a specification.

More particularly my invention relates to hanger-sockets for embedment in concrete 10 ceilings, &c., to support hangers for pipes, shafting, &c.

It is the object of my invention to provide a device of simple construction which may be easily set in place and fixed in the 15 body of concrete in desired position, and which will be secured with sufficient rigidity to sustain the weight which such a device is designed to carry.

It is also an object of my invention to provide a device for the purpose described which may be easily set in place and fixed in the 20 body of concrete in desired position, and which will be secured with sufficient rigidity to sustain the weight which such a device is designed to carry.

It is also an object of my invention to provide a device for the purpose described which may be used with reinforced concrete 25 constructions, in which the reinforcing members are metal bars extending parallel with one another. The device is one which is adapted to embrace or fit about the reinforcing bar, so that it may be applied without difficulty where the reinforcing bars are 30 close together; it is also adapted for use with reinforcing bars of various cross section such as are now commonly used.

In the drawings: Figure 1 is a front elevation, with part in section, of a hanger-socket embodying my invention and showing the manner in which the same is embedded in a concrete ceiling; Fig. 2 is a front elevation of the hanger-socket embedded in the concrete and showing the same used with a reinforcing bar of irregular section; Fig. 3 is a perspective view of the hanger-socket shown in Figs. 1 and 2; Fig. 4 is a side elevation of another form of hanger-socket also embodying the invention; Fig. 5 is a transverse vertical section of the same on the line A—A of Fig. 4; and Fig. 6 is an inverted plan view of the same.

a is a tubular or hollow body which forms the socket proper. This is closed at the top 55 and provided with oppositely directed lateral arms b, b, having at their ends upright

extensions c, c. The top of the body a has a recess d extending transversely to the lateral arms b, b, open at its ends and preferably curved or trough-shaped. In setting 60 the hanger-socket it is placed with the open end of the body a resting on the centering e, and the concrete f is poured in above the centering, which, after the concrete is set, is removed leaving the hanger-socket embedded in the body of concrete. For the purpose of holding the hanger-socket in place against longitudinal displacement while the concrete is being applied, a dowel-pin g may be inserted through the centering 65 into the socket. This may be either a metal pin screwed into the socket or a wooden pin driven in. When the centering is taken down the dowel-pin is removed, leaving the socket open through the lower face of the 70 concrete to receive the hanger or part which is to be suspended from it.

In applying the hanger-socket to reinforced concrete ceilings in which reinforcing metal bars extend parallel to one another 75 through the concrete, the socket pieces may be arranged to embrace the reinforcing bars, as shown in the drawings. With round or twisted bars, the bar may fit in and extend through the recess d as is indicated in dotted lines in Fig. 1, and when the bar is of irregular shape having lateral arms or flanges h, the arms or flanges may extend over the lateral arms b, b, with the central portion of the bar extending through the socket b, as 80 is shown in Fig. 2. The hanger-socket is thus adapted to be fitted about reinforcing bars of different cross-sections such as are 85 now in common use. The upright portions c, c, extend above the reinforcing bars into 90 the body of the concrete, and to fix them more securely therein, they are preferably made of irregular shape or outline; shown, they are provided with notches c' in their edges whereby the upper outer portions of 95 the upright extensions form upper anchoring terminals, as will be apparent to those skilled in the art. The concrete entering these edges aids in fixing the hanger-socket 100 securely in the concrete. The arms b, b, extending laterally from the top of the body of the socket into the concrete are however the principal means, in the construction shown, of fixing the device securely in place. When the concrete is set the socket is so rigidly fixed in place that it is capable of sustaining any reasonable weight.

In the construction shown in Figs. 4, 5 and 6, instead of a tubular tapped body, such as is shown in Figs. 1, 2 and 3, I employ an elongated box-like body a' having a key-slot a^2 to receive the hanger, the head of which may be inserted through the large portion a^3 of the slot and then move longitudinally into the smaller part. For the purpose of strengthening the structure the lateral arms b and the outer wall of the recess d may be connected with the top of the socket body by webs i .

The manner of embedding the hanger-socket of the form shown in Figs. 4, 5 and 6, is the same as that employed with the hanger-socket shown in Figs. 1, 2 and 3, except that instead of a dowel-pin to hold the device against displacement it may be secured to the centering by tacks in the notches j in the sides of the bottom.

It will now be apparent that I have devised a novel and useful construction of a hanger socket which embodies the features of advantage enumerated as desirable in the statement of the invention and the above description, and while I have, in the present instance, shown and described a preferred embodiment thereof which will give in practice satisfactory and reliable results, it is to be understood that the same is susceptible of modification in various particulars without departing from the spirit or scope of the invention or sacrificing any of its advantages.

What I claim is as follows:

1. As an improved article of manufacture, a hanger socket for embedment in concrete ceilings and the like, comprising a body portion having a hollow member depending therefrom, the top surface of said body portion having a trough-shaped recess therein and the walls of said recess being extended laterally on opposite sides thereof to form lateral supporting arms and upright extensions projecting from said arms, the edges of said upright extensions having notches therein whereby upper anchoring terminals are formed, the notches in said upright extensions being adapted for the reception of concrete, whereby the device after being

placed in position and surrounded with concrete is locked against vertical and lateral displacement.

2. The combination of a hanger socket for embedment in concrete ceilings and the like, comprising a body portion having a hollow member depending therefrom, the top surface of said body portion having a trough-shaped recess therein and the walls of said recess being extended laterally on opposite sides thereof to form lateral supporting arms, said arms having upright extensions thereon, the opposite edges of said upright extensions having notches therein whereby upper anchoring terminals are formed, the notches in said upright extensions being adapted for the reception of concrete, whereby the device after being placed in position and surrounded with concrete is locked against vertical and lateral displacement, and a bar supported in said trough-shaped recess and extending transversely thereto.

3. The combination of a hanger socket for embedment in concrete ceilings and the like, comprising a body portion having a hollow member depending therefrom, the top surface of said body portion having a trough-shaped recess therein and the walls of said recess being extended laterally on opposite sides of said trough-shaped recess to form lateral supporting arms, said arms having upright extensions, the opposite edges of said extensions having notches therein, whereby upper anchoring terminals are formed, said notches being adapted for the reception of concrete whereby the device after being placed in position and surrounded with cement is locked against vertical and lateral displacement, and a bar supported in said trough-shaped recess and extending transversely thereto, said bar having laterally extending flanges adapted to be supported upon the laterally extending socket arms.

In testimony of which invention, I hereunto set my hand.

CHAS. W. DENNY.
